UNITED STATES PATENT OFFICE

JOHN W. SHAW, OF NORWOOD, NEW JERSEY

BED CONSTRUCTION

Application filed May 26, 1928. Serial No. 111,828.

This invention relates to improvements in collapsible bed constructions.

It is an object of the invention to provide a collapsible bed, which is conveniently extended from collapsed position, without the need for thereafter first making up the companion bed sections or either of them, and which in the extended as well as in the collapsed state, affords all of the comfort of superior constructions of non-collapsible beds.

Another object is to provide a collapsible bed which imposes no restriction on the thickness of approved spiral or box-springs and mattresses employed therewith, and which in extended condition, will afford a normal height of bed without unduly, if at all, increasing the overall height of the collapsed bed.

Another object is to provide a bed of the above type in which the companion bed section is securely sustained in collapsed state of the bed, directly upon rigid structure therebelow.

Another object is to provide a bed of the type noted, which may be collapsed or extended by a single simple manual operation involving little effort, though the bed be of heavy construction.

In a preferred embodiment, I carry out the objects noted, by the use of a collapsible bed of that general type in which a companion or extension section is moved from collapsed to extended position by a parallel motion in a curved path and in which the bed spring of the main frame is automatically operated from the parallel motion linkage to rise from a lower inobtrusive position to substantially the level occupied by the companion bed spring in fully extended position.

With a thick couch portion including either or both a thick spiral bed spring and a superposed thick mattress, were the companion couch portion superposed on top of the upper-

most level of the main couch portion, the collapsed bed would be unduly high.

To dispose the companion couch portion at low level in the collapsed bed, the main couch portion must rise in the extended bed to occupy part or all of the space previously vacated by the companion couch portion in its traverse from collapsed state of the bed. Where the extension of the companion couch and the rise of the main couch occur simultaneously, in a single operation, it becomes important to so inter-relate the movements that clashing between the edges of the couch portions is avoided at all parts of the extension and of the collapsing movement. According to my invention, the gap between the two springs exceeds the thickness of mattress and made-up bedding on the main spring, not only in the collapsed setting of the bed, but throughout the transit of the upper over the lower spring in the shifting movement to collapsed or to extended position.

In a preferred specific construction according to my invention, the parallel motion linkage is arranged to effect a lateral displacement of the companion couch portion in movement from fully collapsed to fully extended position, through a range substantially greater than the width of either of the beds. The result is thereby accomplished not only of affording the required clearance in the movement past each other of thick and previously made-up couch portions, but in addition the extended position affords a pair of twin beds rather than a single bed of double width, said twin beds spaced apart sufficiently for the maid to step therebetween to tuck in the bedding, in making up the two bed sections prior to collapsing the construction.

Other objects and advantages of this invention will be apparent during the course of the following detailed description.

In the accompanying drawings, forming a part of this specification, and wherein similar reference characters designate corre-

sponding parts throughout the several views, Figure 1 is a fragmentary end elevation of the improved bed construction, showing the two movable bed frames in an extended relation to provide a bed construction, the sections of which simulate twin beds.

Figure 2 is an end view of the operating mechanism of the improved bed construction, showing the collapsed superposed positioning of the movable bed frames.

Figure 3 is an end elevation of the bed construction, showing the operating mechanism in its half-way open position with the bed sections half way opened.

Figures 4 and 5 are cross sectional views taken substantially on their respective lines in Figures 2 and 1 of the drawings.

In the drawings, wherein for the purpose of illustration is shown only a preferred embodiment of this invention, the letter A 20 may generally designate the improved bed construction, which may comprise a main or stationary frame B, to which lower and upper movable bed frames C and D are connected by operating mechanism E.

Referring to the main frame or stationary frame B, the same at each end of the bed includes the end supports 15, which are preferably formed of angle metal bent into U-shaped formation, to provide a top bar 16, having the supporting legs 17 and 18 which extend in parallel relation. These end supports 15 are preferably connected by horizontal side rails 18 and 19, connected at the lower ends of the legs 17 and 18, and extending in parallel relation along opposite sides of the bed, as can readily be understood. The end supports 15 furthermore each preferably comprise a lower cross bar 20 secured in any approved manner at its ends to the lower ends of the legs 17 and 18, to rigidly brace the same, or these end cross bars 20 may be suitably connected to the rails 18 and 19, in any approved manner, to provide a substantially rectangular shaped floor structure for the frame, to which the end supports 15 are connected at the lower ends of the legs 17 and 18. As can readily be understood from the drawings, guide rails 21, preferably of straight line formation are connected at the outer sides of each of the legs 17 and 18, and vertically extending from the lower ends of said legs to adjacent the top bars 16, the same preferably being arcuated in cross section to serve as guide rails for the movement of the movable frame C, as will be subsequently described.

As a reinforcing means and to facilitate connection of parts of the operating mechanism E, each of the end supports 15 of the main frame B comprises a vertical reinforced bar or member 25, connected at its lower end at 26 to the cross bar 20, and at its upper end being connected at 27 to the top bar 16, as is illustrated in Figure 1 of the drawings. This

vertical bar 25 is mounted parallel with the legs 17 and 18 of the end supports 15, but is preferably disposed between said legs, closer to the leg 18 than the other leg 17, that is, the same is disposed closer to that side of the main frame from which the upper movable bed section C extends when the bed is opened. Furthermore, the end supports 15 have a horizontal supporting and reinforcing bar 28 connected at one end to the vertical bar or member 25, and at its opposite end preferably being connected to the leg 18, in a position parallel with the bars or members 16 and 20, although preferably closer to the floor across bar or member 20 than the top support bar 16, as is illustrated in Figure 1 of the drawings.

The movable frame C may be termed the inner or lower or movable frame, and it comprises the end rails 30, connected by the longitudinal side rails 31 and 32; the frame C being adapted to slide vertically without tipping from a horizontal plane. The end rails 30 operate adjacent the insides of the stationary frame end support 15, and the longitudinal side rails 31 and 32 are so connected therewith that they extend outwardly beyond the planes of the end frame supports 15, and there are provided with suitable rotatable rollers 33, which roll over the guide tracks 21, which are preferably arcuated in cross section to accommodate the groove of the rollers 33, as can readily be understood. The movable frame C of course has the rail construction thereof so formed as to receive a mattress, and conventional bed springing for the mattress preferably of the approved spiral spring type shown, and the same is movably supported for vertical extension by part of the operating means E to be subsequently described.

The other movable frame D may be referred to as the upper or outer or companion movable frame, and this comprises the end rails 37 and 38, connected by the longitudinal side rails 39 and 40, in any approved relation of parts to receive conventional bed spring material, and mattress identical with those of the main frame.

The horizontal support for the occupant of the bed including the bed spring I have designated in certain of the claims as "couch portion".

The movable frame D is supported by part of the operating means E consisting of the parallel supporting bars or members 41 and 42, which at their upper ends are pivotally connected at 43 and 44 respectively to the ends of the frame D, it being understood that the pair of supporting bars 41 and 42 are similarly provided at each end of the bed. The supporting arms 41 are preferably connected at an end of each of the end rails 37 and 38, that is, at two corners of the bed frame D, and the other legs 42 are connected

at 44, in pivotal manner, at points intermediate the ends of the end rails 37 and 38, not quite half way, and closer to the pivotal connections 43 than the opposite side of the frame. At their lower ends the supporting bars 41 and 42 are pivotally connected at 46 and 47 respectively to the outer ends of the short horizontal supporting bar or member 28, so that it can readily be understood that the supporting bars or members 41 and 42 are pivotally connected at their lower ends to one side of the longitudinal center of the main frame B, and at the upper ends of said legs are likewise pivotally connected to the upper frame D, to the opposite side of the longitudinal center of the said movable frame D, so that the movable frame D when in supported relation upon the top bars 16 of the end frame supports 15 is positioned in a horizontal plane thereover, with the legs 41 and 42 diagonally extended from their connection to the frame D, across the ends of the main frame, for connection at 46 and 47 to the main frame B, in the relation of parts illustrated in Figure 2 of the drawings, and whereby upon lifting upwardly upon the movable frame D, by an operator pulling on the handles 50, it is readily apparent that the supporting bars 41 and 42 will enable an upward pivotal swing of the movable frame D, without tipping the same from a horizontal plane; the supporting members 41 and 42 first moving from the diagonal position at the end support's 15, to vertical position, and thence downwardly beyond the main frame B, to a diagonal position for supporting the movable frame D in an extended horizontal position outwardly beyond a side of the main frame B, in position for use.

Each pivot connection 46 also preferably extends thru the vertical supporting member 25 of the end frame portion 15, and each leg 41 has an arcuated extension 50 at the opposite side of its pivot axis 46 from the end which supports the frame D, to which is connected a transverse extension 51, intermediate the ends of the extension 50, and in acute angular relation with respect to the supporting bar 41; the extension 51 having a roller 55 at the end thereof adapted to roll upon the downwardly facing arcuated cam surface 56 of a cam providing bracket 57 which is riveted or secured at the outer side of each of the main frame ends 15 in the relation of parts illustrated in Figure 3; the wheels 55 when the upper movable frame D is closed in a collapsed position upon the main frame B, as illustrated in Figure 2, being preferably in engagement with ends of the arcuated track surfaces 56, and so that upon lifting of the movable frame D to an extended position the wheels 55 will move upwardly incident to swing of the legs 41 on the pivots 46, to likewise lift the ends of the lower movable frame C, upwardly, to

cause the upward lift of the same at the same time that the other movable frame D is being extended, as is perfectly obvious.

To facilitate the opening and closing movements of the movable frames C and D, the free end of each bar extension portion 50 is preferably connected with oppositely disposed springs 60 and 61, preferably respectively connected by cables or chains 62^a and 63^a, with said free end of the extension portion 50; said springs 60 and 61 preferably lying along the lower cross rail 20 at each end of the main frame, and of course at opposite sides of the pivot connection 46 of the leg 41; said springs 60 and 61 at their outer ends having threaded shanks 62 for adjustable engagement by nuts 63 in the lower ends of the angle supporting legs 17 and 18 of the main frame B. When the movable frames C and D are collapsed in superposed parallel relation, as illustrated in Figure 2 of the drawing, the extension portion 50 of the supporting bar 41 will have been so positioned as to tension the spring 60, and this tension may be varied by means of the adjustable shank and bolt means by which the said spring 60 is connected to the lower end of the main frame leg 17, as is obvious. In this relation of parts, with the movable frames collapsed, the spring 61 is likewise collapsed and not under tension. The spring 60 due to the tension thereof when the movable frames C and D are collapsed, exerts its force in a tendency to swing the bed frame supporting bar 41 on its pivot 46, to move the movable frame D upwardly, and likewise due to the engagement of the roller 55 against the surface 56, to also move the lower movable frame C upwardly. This tension is slightly less than the force required to overcome the inertia of the movable frames C and D, so that when the operator grasping the handles 50 lifts upwardly upon the upper movable frame D, it requires but little manual effort to overcome the inertia of the movable frames C and D, in order to lift the same upwardly, to their extended relation illustrated in Figure 3, and at which position it is to be noted that the tension of the spring 60 has been released, and the movement of the upper movable frame D from this position is downwardly, moving the extension 50 of the supporting bar 41 in an opposite direction, to tension the other spring 61, which due to the force required to tension the same buffs the shock of the extended positioning of the movable frame D for positioning for use, in the relation of parts illustrated in Figure 1. Thus, when the movable frame D is extended for use the springs 61 are tensioned, and the tension of the same is exerted in an effort to swing the extension 51 to an upward position, so that to collapse the bed frame D it requires little manual effort to lift the same upwardly and swing it to a collapsed po-

sition, as is quite evident. It is to be noted that during the entire act of swinging of the movable frame D from a collapsed to an extended position, the rollers 55 at the ends of the main frame act upon the shaft surfaces 56 to cause a lift of the other movable frame C to its horizontal position for use as illustrated in Figure 1 of the drawings, and in which position the frames C and D are in the same plane, but at their facing longitudinal edges they are spaced, to give a twin bed effect when the beds are made up, since it is intended that individual bedding shall be provided for each of the movable bed frames C and D, so that the same may be made up ready for use, and extended and collapsed at will, depending upon whether an individual or a dual use of the bed is to be made.

10 The lower movable frame C is of course provided with other support means than the operation of the roller 55 on the cam surfaces 56, and this other-supporting means consists in the provision of collapsible link arrangements 65 and 66 at each of the frame ends 15; these collapsible link supports 65 and 66 consisting in the provision of lower section 67 pivotally connected at their lower ends on the base rail 20 of the frame ends 15. The 15 said link constructions 65 and 66 also include upper sections 68 pivotally connected at their upper ends at 69 to the end rails 30 of the movable frame C; the proximate ends of the said links 67 and 68 being connected at 70 to each other, in such relation that the sections 67 and 68 of each of the collapsible link supporting devices 65 and 66 will swing into a substantially V-shaped relation when the movable bed frame C is collapsed, and upon 20 the extension of the movable frame C, said links 67 and 68 tending to move into vertical alignment, but not quite being vertically aligned, for a reason which will more presently appear.

25 The means provided to lock the collapsible link devices 65 and 66 to hold the movable frame C in an extended horizontal position consists in the provision of a horizontal lock bar 75, at each of the ends of the main frame, 30 for the pair of collapsible links 65 and 66 disposed thereat, each of said lock bars 75 including horizontal slots 76 and 77 therealong adapted to receive therein the extended ends 35 of the pivot pins 70 of the collapsible link devices 65 and 66 respectively. At their outer ends the slots 77 are provided with downwardly extending right angled offsets 80, into which the extended offset ends of the pins 70 may ride when the links 67 and 68 of each of 40 the link devices 65 and 66 are extended to their maximum relation; tension springs 82 being provided at each of the remote ends of the lock bar 75; said springs at their opposite ends being connected adjacent the upper 45 pivoted ends of the respective link sections 68, so that as the links of the link devices 65 and 66 move to an extended position, the springs 82 will be gradually tensioned, for exerting an upward pull upon the lock bars 75, in order to force the offset recessed ends 70 of the grooves of the lock bars to receive the extended ends of the pivot pins 70 when the links of the link devices 65 and 66 are practically vertically aligned, as is illustrated in Figure 1 of the drawings, and thus to lock 50 said link devices 65 and 66 in position against accidental collapsing, in order to hold and bear the entire support of the movable frame C when the same is extended, as is illustrated in Figure 1 of the drawings. The pivoted ends of the link 65 and 66 move towards each other when the frame C is being collapsed, and move away from each other when the movable frame C is being extended.

55 Means is provided to move the lock bar 75 downwardly in order to disconnect the link devices 65 and 66 from their locked connection in the offset ends of the grooves 77, consisting in the provision of an arm or bracket 90 carried at the inner side of the roller 55, preferably by the pin which supports said roller, which is adapted to give a bracket extension 91, which is carried by the lock bar 75, a glancing blow as the wheel 55 is moved downwardly incident to the elevating of the movable frame D from an extended to a collapsed position, and which glancing blow of the extension 90 on the extension 91 will cause the lock bar 75 to move downwardly against the tension of its springs 82, until the ends of the pivot pins 70 are removed from the offset extensions 80 of the grooves 77, and then the frame C will fall downwardly until the arcuated surfaces 56 of the brackets 57 of said frame C again engage the rollers 55, which in the meantime have moved slightly downwardly. It is to be noted that the falling of the frame C immediately after the lock bar 75 has been released, is enabled, due to the fact that the link sections 67 and 68 of each of the link devices 65 and 66 are not positioned truly in vertical alignment, but are in slight V-shaped relation when the frame C is extended to its uppermost position, as illustrated in Figure 1, so that the weight 60 of the frame C always acts upon the link constructions 65 and 66, even when extended, tending to move the same in a collapsed position.

65 From the foregoing description of this invention it is believed that the operation will be apparent. From the collapsed position illustrated in Figure 2 the operator merely lifts upwardly upon the handle 50, and due to the balance support of the frames C and D 65 by means of the springs 60, the upward lift merely requires a slight manual effort, aided by the contraction of the springs 60, to move the frames C and D upwardly, without tipping them from their horizontal position.

When the supporting bars 41 and 42 are vertically aligned with the bed sections C and D in a half way open position, the section D falls downwardly and the section C continues 5 to rise, and this begins to place the springs 61 under a tension to buff the falling action of the frame D, and the elevation of the bed frame C coming into extended position. The lower movable frame C has a guided relation 10 by means of the rollers 33 operating on the vertical tracks 21, and in extended position the sections C and D are in the same horizontal plane.

It will be seen that in the movement of 15 the companion frame from collapsed to extended position, the main couch portion C including the mattress and the spiral spring thereof is raised into the space vacated by the companion couch portion D. Throughout the 20 transit of the upper or companion spring over the lower or main spring, the linkage, however, determines a gap between the springs, which exceeds the thickness of mattress and made-up bedding on the main spring 25 whereby clashing is avoided. The links 41-42 are of sufficient length to just permit the lower left edge of the companion couch portion to pass the upper right-hand edge of the rising mattress and made-up bedding on 30 the main couch portion. The main and companion sections of the extended bed are readily made up, as readily as if the beds were separate and distinct, the maid conveniently stepping into the space between the two sections for tucking in the bedding. Thereupon, 35 the companion bed section is raised and pushed inward by a simple single thrust and the bed collapsed without in any way deranging the made-up bedding. As in the extension movement previously set forth, the right lower edge of the extension spring would just clear the left upper edge of the mattress and made-up bedding on the main couch portion.

In the collapsed bed, the companion frame 40 is supported securely at both its lateral edges upon the main frame portions directly therebelow and more specifically upon the top bars 45 of the end frame supports 15. Thus, rattling and looseness is avoided, which may be 50 incurred where the companion bed spring is supported by the linkage in a cantilever arrangement.

End boards 95 may be provided for the 55 movable section D, to aid in the support and better appearance of the same, when extended, and similar end boards 96 may be provided for the ends of the main frame construction B.

Various changes in the shape, size, and arrangement of parts may be made to the form 60 of invention herein shown and described, without departing from the spirit of the same or the scope of the claims.

I claim:

65 1. A collapsible bed construction compris-

ing a main frame, a bed spring movably carried thereby, a companion frame, a bed spring carried thereby, said springs of equal width and length, parallel motion linkage connecting said frames, and determining a translational movement of said companion frame in a curved path in the travel from fully collapsed to fully extended position, through a lateral range greater than the width of either of said springs, transmission means connecting 70 said parallel motion linkage with the spring of said main frame to cause the latter to move downward to inobtrusive position with respect to the superposed companion spring in the collapsed position, and to cause said main 75 spring to be raised in the extension of the bed until it reaches a level common with that of the fully extended companion bed, the difference in level between the two springs throughout the transit of the upper over the lower in the shifting movement to collapsed or to extended position, being greater than the thickness of mattress and made-up bedding on the main spring.

2. A collapsible bed comprising a main 80 frame having a couch portion movably mounted thereat and including a spring and a mattress, a companion frame having a couch portion including a spring and a mattress of the same width as that of said main frame, the lateral edges of the couch portion of said companion frame in collapsed condition of the bed being supported upon the corresponding parts of the main frame directly 85 therebelow, linkage connecting said two frames and the couch portion of the main frame to cause the latter to rise into the space vacated by the companion frame as the latter is moved to extended position, until said main couch portion reaches a level common with that of the extended companion frame, said linkage determining a lateral displacement 90 of the companion frame substantially greater than the width of either of said frames and affording clearance throughout in the movement of the inner lower edge of the companion couch portion with respect to the contiguous upper edge of the main couch portion, as the latter rises into the space vacated by the former.

3. A collapsible bed construction comprising a main frame including a couch portion movably mounted thereat and comprising a spiral bed spring and a mattress thereon, a companion bed frame including a couch portion comprising a spiral bed spring and a mattress thereon, said couch portions being of the same length and width, parallel motion linkage connecting said frames together, said companion frame being superposed directly over said main frame in collapsed condition of the bed, transmission means connected with said linkage, serving to lower the main couch portion in the collapsing movement of the bed, to be clear of the super- 115 120 125 130

posed couch portion, and to raise said main couch portion in the opening or extension movement of the bed, into the space vacated by the other couch portion and to an upper 5 level common therewith in the extended position thereof, said parallel motion linkage determining a lateral displacement of the companion bed from collapsed to extended position through a range greater than the 10 width of the bed.

4. A collapsible bed construction comprising end structures and a couch portion movably mounted therebetween and having end rails and side rails, a companion frame having a couch portion with end rails and side rails of the same length and width as those of the main couch portion, parallel motion linkage connecting said frames together, to dispose said couch portions in superposed 15 relationship with the rails of the companion couch portion sustained upon the tops of the end structure, linkage connecting said parallel motion linkage with the main couch portion to dispose the latter at the lower part 20 of the main frame for clearance with respect to the companion couch portion, said linkage serving to lift the main couch portion as the companion couch portion is moved, to assume a common level with the companion couch 25 portion in extended position, the upper surface of the main couch portion in extended position of the bed being substantially above the lower limiting plane of the companion couch portion when the bed is in collapsed 30 position, said parallel motion linkage determining a lateral displacement of the companion frame from completely collapsed to completely extended position through a path 35 greater than the width of either frame.

5. A collapsible bed construction comprising end structures and a couch portion therebetween including a spiral bed spring and having end rails and side rails, a companion frame having a couch portion including a 40 spiral bed spring and having end rails and side rails of the same length and width as those of the main couch portion, parallel motion linkage connecting said frames together to dispose said couch portions in superposed 45 relationship with the rails of the companion couch portion sustained upon the tops of the end structures, linkage connecting said parallel motion linkage with the main couch portion to dispose the latter at 50 the lower part of the main frame for clearance with respect to the companion couch portion, said linkage serving to lift the main couch portion as the companion couch portion is moved, to assume a common level with the companion couch portion in extended position, the upper surface of the main couch portion in extended position of the bed being substantially above the lower limiting plane 55 of the companion couch portion when the bed is in collapsed position, said parallel mo-

tion linkage determining a lateral displacement of the companion frame from completely collapsed to completely extended position through a path greater than the width of either frame.

6. A collapsible bed construction comprising a main frame having end structures and side bars, a couch part having end and side rails movably mounted on said main frame and including a spiral bed spring having the 70 lengths of the spirals thereof extending below said rails, a companion frame having end and side rails and a spiral bed spring thereon of the same dimensions as that of the main frame and with the spirals thereof extending 75 below the rails therefor, parallel motion linkage connecting said frames, and linkage operated from said parallel motion linkage and connected to the main couch part to move the latter upward within the frame during the 80 extension movement of the companion frame, to dispose the rails of said main couch part at substantially the level occupied in collapsed position by the rails of the companion couch part, the parallel motion linkage determining 85 a course of lateral displacement of the companion frame from fully collapsed to fully 90 extended position greater than the width of said frame, the linkage for displacing the main spring effecting a gradual lifting movement 95 thereof, performed substantially throughout the displacement of the companion frame from fully collapsed to fully extended position.

7. A collapsible bed construction comprising a main frame having a couch portion movably mounted thereat, a companion frame having a couch portion, parallel motion linkage connecting said frames, disposing the couch portions in superposed relation in collapsed condition of the bed, with the main couch portion depressed below the companion couch portion, said linkage being constructed and arranged to elevate the depressed couch portion during the extension of the bed 100 105 to substantially the level of the companion couch portion in collapsed position, and automatic latch means for locking the main couch portion in its uppermost position when the bed is extended, and arranged to be automatically tripped as the bed is collapsed.

8. A collapsible bed construction comprising a main frame having a couch portion movably mounted thereat, a companion frame having a couch portion, parallel motion linkage connecting said frames, disposing the couch portions in superposed relation in collapsed condition of the bed, with the companion portion supported at its lateral edges by the main frame parts directly therebelow, 110 and the main couch portion depressed below the companion couch portion, said linkage being constructed and arranged to elevate the depressed couch portion during the extension 115 of the bed to substantially the level of the 120 125 130

companion couch portion in collapsed position, and automatic latch means for locking the main couch portion in its uppermost position when the bed is extended and arranged 5 to be automatically tripped as the bed is collapsed.

9. A collapsible bed construction comprising a main bed frame having a head board and a foot board and including a main bed 10 spring movably mounted thereon, a companion bed frame having a head board and a foot board and including a bed spring thereon, parallel motion linkage connecting said frames for outward and inward movement of 15 the companion frame respectively to extended and collapsed setting, a bed spring for said companion frame, a bed spring for said main frame, said latter spring in collapsed setting of the bed being below the lower part 20 of the companion bed spring by an interval sufficient to accommodate a mattress therebetween, means connecting the linkage with the main bed spring to cause the latter to rise automatically as the companion frame is 25 moved to extended position, the head and foot boards of said companion bed section sustaining the same upon the floor when in extended position, said companion bed frame supported at both lateral edges in collapsed 30 position by the main frame parts substantially directly therebelow, said main bed frame affording space between the end boards and the linkage to accommodate the head and foot boards of the companion bed section in 35 collapsed position.

10. In a bed construction the combination of a main frame, a movable bed section, an arm pivotally connected to the bed section and pivotally connected to the main frame to 40 permit collapsed or extended positioning of the bed section with respect to the main frame, said arm having an extension thereon at the opposite side of its pivot from the main frame, springs, means connecting said springs 45 at their outer ends on the frame at opposite sides of the pivot connection of the said arm on the main frame, means connecting the inner ends of said springs to the extension of said arm in such relation that one of the 50 springs will be tensioned when the bed section is swung to one side of its pivot and the other spring will be tensioned when the bed section is swung to the opposite side of the pivot of its arm, a second bed section 55 movably mounted on the main frame for rise and fall thereon, and cam means carried by the second mentioned bed section and by the extension of the arm of the first mentioned bed section for causing a synchronous extended and collapsed movement of the said 60 bed sections.

11. In a day bed construction the combination of a main frame, a bed section movably mounted within the main frame, spaced collapsible link devices at each end of the main

frame connecting the bed section for rise and fall within the main frame, means to releasably lock said link devices in extended position for upwardly supporting the bed section with respect to the main frame, including a lock member, means operated by the extension of said link devices to bring the lock member into locking operation with said link devices, a second movable bed section, means movably connecting said bed section on the 70 main frame, means carried by the last mentioned means for operation on the first mentioned bed section to cause synchronous movement thereof when the first mentioned bed section is moved to an extended position with respect to the main frame, and means carried by the last mentioned means and co-operating with said lock member to cause the lock member to release the link devices as the second mentioned bed section is moved from 75 an extended to a collapsed position.

12. In a bed construction the combination of a main frame, a movable bed section, track and roller means carried by the main frame and movable bed section for permitting the guided vertical movement of the bed section with respect to the main frame, collapsible link devices at each of the ends of the main frame, each being connected with the main frame at one end and with the movable bed section at their opposite ends to extend and collapse said link devices as the bed section rises and falls with respect to the main frame, an elongated lock member at each end of the main frame, having a groove therein for each link device adjacent thereto, each groove having an offset groove end therein, an extension carried by each link device operating in said groove during rise and fall of the bed section in the main frame, the bed section when extended to its highest extent in the main frame having the extensions of said link devices in the offset ends of the grooves to lock the said bed section in elevated position, spring means connected with the lock member and with the link devices to cause the lock member to move to permit said extensions of the link devices to move into the offset groove ends upon the elevation of the bed section, and means to release said lock member to permit the bed section to fall and the link devices to collapse.

13. A collapsible bed construction comprising a main bed frame having a couch portion movably mounted thereon, a companion frame having a couch portion, each of said couch portions including a bed spring, the spring of the main frame in collapsed setting of the bed being below the spring of the companion frame by an interval sufficient to accommodate therebetween a thick mattress and the corresponding made-up bedding, parallel motion linkage pivoted to said main frame and determining the outward and inward movement of the companion frame by 120 125 130

- 3 a translational displacement in a curved path through a range substantially greater than the width of either of said couch portions, and means connecting the linkage with the couch portion of the main frame to cause the latter to rise automatically as the companion frame is moved to extended position into the space vacated by said companion couch portion. 70
- 5 14. A collapsible bed construction comprising a main bed frame having a couch portion movably mounted thereon, a companion frame having a couch portion, each of said couch portions including a spiral bed spring, the spring of the main frame in collapsed setting of the bed being below the spring of the companion frame by an interval sufficient to accommodate therebetween a thick mattress and the corresponding made-up bedding, parallel motion linkage pivoted to said main frame and determining the outward and inward movement of the companion frame by a translational displacement in a curved path through a range substantially greater than the width of either of said couch portions, and means connecting the linkage with the couch portion of the main frame to cause the latter to rise automatically as the companion frame is moved to extended position through a height at least equal to the combined thickness of the mattress and of the spiral spring into the space vacated by said companion couch portion. 75
- 10 15 20 25 30 35 40 45 50 55 60 65 70 75 80 85 90 95 100 105 110 115 120 125 130
16. A collapsible bed construction comprising a main bed frame having a couch portion movably mounted thereon, a companion frame having a couch portion supported at both lateral edges thereof by the main frame part substantially directly therebelow, each of said couch portions including a spiral bed spring, the spring of the main frame in collapsed setting of the bed being below the spring of the companion frame by an interval sufficient to accommodate therebetween a thick mattress and the corresponding made-up bedding, parallel motion linkage pivoted to said main frame and determining the outward and inward movement of the companion frame by a translational displacement in a curved path through a range substantially greater than the width of either of said couch portions, and means connecting the linkage with the couch portion of the main frame to cause the latter to rise automatically as the companion frame is moved to extended position into the space vacated by said companion couch portion. 140
17. A collapsible bed comprising a relatively fixed main frame, a primary spring bed frame having means by which it is supported for vertical movement in the main frame, an extension spring bed frame having substantially the length and width of the primary frame, a pair of parallel links at each end of the bed pivoted at their lower ends on the main frame and at their upper ends on the extension frame whereby the extension frame may be swung from its collapsed position in which it is superposed on the main frame and spaced above the primary spring bed frame to an extended position in which it is in front of and spaced horizontally from both the fixed frame and the primary frame, means for supporting the extension frame in that position and means whereby swinging the extension frame from its collapsed to its extended position vertically raises the primary frame to a position substantially the same as that occupied by the extension frame when collapsed and a reversal of the swinging movement lowers the primary frame to a collapsed position directly below and spaced from the extension frame, the bed when in extended form presenting two substantially like and horizontally spaced spring bed frames. 145
18. A convertible couch and twin bed construction including a main frame, a primary bed section mounted in the frame including a deep spring adapted to support a mattress, a secondary generally similar extension bed section also including a spring adapted to support a mattress, means to normally support said sections and their bed clothing in superposed relationship with the primary bed section including its made-up bed clothing in non-interfering relationship with the superjacent extension bed section, means movably connecting said extension bed section to the main frame to allow for and guide movement of the extension bed section to an 150

- extended position wherein it is laterally spaced from the primary bed section, and means operable, upon movement of the extension section to extended position, to elevate the primary bed section into the space vacated by the extension section, said sections in extended position presenting a pair of twin beds, spaced apart sufficiently to be made up with separate sets of bed clothes and of a height substantially the same as the height of the extension section when collapsed.
